UNITED STATES PATENT OFFICE

139,038

DESIGN FOR A DEODORIZER

Walter E. Anderson, Kansas City, Mo., assignor
to Anderson-Stoltz Pharmaceuticals, Inc., Kan-
sas City, Mo., a corporation of Missouri

Application June 30, 1944, Serial No. 114,259

Term of patent 14 years

(Cl. D16—2)

To all whom it may concern:

Be it known that I, Walter E. Anderson, a citizen of the United States, residing at Kansas City, in the county of Jackson and State of Missouri, have invented a new, original, and ornamental Design for a Deodorizer, of which the following is a specification, reference being had to the accompanying drawing forming a part thereof.

Fig. 1 is a front elevational view of the deodorizer, showing my new design.

Fig. 2 is a side elevational view thereof; and
Fig. 3 is a top plan view thereof.

I claim:

The ornamental design for a deodorizer, as shown.

WALTER E. ANDERSON.
